UNITED STATES PATENT OFFICE.

JOHN LISTIAK, OF YOUNGSTOWN, OHIO.

SNAP-HOOK.

1,223,812.

Specification of Letters Patent. Patented Apr. 24, 1917.

Application filed June 21, 1916. Serial No. 104,874.

To all whom it may concern:

Be it known that I, JOHN LISTIAK, a citizen of the United States, residing at Youngstown, in the county of Mahoning and State of Ohio, have invented certain new and useful Improvements in Snap-Hooks; and I do hereby declare the following to be a full, clear, and exact description of the invention, such as will enable others skilled in the art to which it appertains to make and use the same.

This invention relates to new and useful improvements in snap hooks and the principal object of the invention is to provide a snap hook particularly adapted for use in hanging scaffolds and the like which is so constructed as to prevent a rope or chain from accidentally becoming disconnected.

Another object of the invention is to provide a snap hook having a lever actuated tongue which tongue is adapted to close the snap hook and to provide a spring means for normally tending to move the tongue into closed position.

Another object of the invention is to provide a lever having an offset extension on its active end which is adapted to engage a downwardly extending finger formed at the rear end of the tongue which finger is rounded at its end to reduce friction.

A still further object of the invention is to provide a tongue which may be actuated by the lever in such a manner as to give the maximum amount of movement to the tongue with a minimum amount of movement of the lever.

With these and other objects in view, the invention consists in the novel combination and arrangement of parts which will be fully set forth in the following specification and accompanying drawing, in which:

Figure 1 is a side view partly in section of a snap hook constructed in accordance with this invention showing the tongue in closed position, and

Fig. 2 is a view similar to Fig. 1 showing the tongue in open position.

Referring now to the drawing, the numeral 1 designates the body of the snap hook provided at one end with the loop 2 the opposite end of the body being formed with the hook member 3. The body 1 is provided with the longitudinal groove 4 which terminates at its forward end in the opening 5 for the accommodation of the extension fingers on the lever and tongue which will

be more fully hereinafter described. The tongue above referred to is pivoted as at 6 near the forward end of the opening 5 and is designated by the numeral 7 and this tongue is provided with the angularly extending arm 8 having the inwardly extending lug or finger 9 formed at its extreme rear end, the lower edge of which is curved as at 10 to bear on the forwardly extending finger of the lever which will be more fully hereinafter described. A suitable spring 11 is arranged to normally urge the tongue to close position as shown in Fig. 1 and to yieldably hold said tongue in such position.

Pivoted as at 12 within the groove 5 at a point near its forward end is the lever 13 provided at its extreme forward end with the inwardly offset portion 14 which is in turn provided with the forwardly extending finger 15 against the upper surface of which the curved end 10 of the lug 9 bears.

It will be apparent from the foregoing that in use the snap hook is manipulated in the ordinary manner and is so arranged that a cord or link may be entered into the snap hook without operating the lever 13 as the tongue 7 will rock on its pivot 6 thus moving the lug 9 away from the finger 15. Should it be desired, however, to release the hook a slight pressure on the lever 13 will cause the tongue to swing on its pivot due to the engagement of the finger 15 with the rounded end 10 of the lug 9 and it will be evident that in this way the snap hook may be readily released. In view of the curved or rounded end of the lug 9 it will be apparent that friction is reduced to a minimum at the point where the lug and finger contact and it will also be evident that this particular structure will allow the maximum amount of movement of the tongue 7 with a minimum movement of the lever 13. It will thus be seen that a particularly simple and durable structure is provided which may be easily manipulated and the wear on the part will be reduced to a minimum.

While in the foregoing there has been shown and described the preferred embodiment of this invention, it is to be understood that such changes may be made in the combination and arrangement of parts as will fall within the spirit and scope of the appended claim.

What is claimed is:

A snap hook comprising a body, a hook at one end of the body, a spring pressed tongue pivoted at one end to the body, an 5 arm extending angularly from the pivoted end of the tongue, a lug extending from the free end of the arm, a lever pivoted at one end to the body, and an offset finger located at the pivoted end of and angularly

related to the lever, and having its side engaged by said lug and being freely movable with relation to said lug.

In testimony whereof I affix my signature in presence of two witnesses.

JOHN LISTIAK.
